UNITED STATES PATENT OFFICE.

EDWARD H. GALLIGAN, OF PROVIDENCE, RHODE ISLAND.

SURGICAL APPLIANCE.

1,323,853.

Specification of Letters Patent.

Patented Dec. 2, 1919.

Application filed October 29, 1917. Serial No. 198,950.

To all whom it may concern:

Be it known that I, EDWARD H. GALLIGAN, a citizen of the United States, residing at Providence, in the county of Providence and State of Rhode Island, have invented new and useful Improvements in Surgical Appliances, of which the following is a specification.

This invention relates to surgical appliances, the object in view being to produce an appliance especially designed for the treatment of diseases of an infectious character and especially diseases which require careful, constant and regular treatment.

15 A further object of the invention is to provide an appliance embodying great adaptability so that difficult places may be reached and antiseptically treated by anyone of average intelligence without danger 20 of injury to the person treated.

With the above and other objects in view, the invention consists in the novel construction, combination and arrangement of parts, herein described, illustrated and claimed.

25 In the accompanying drawings:—

The figure is a sectional view of the improved appliance adapted for the antiseptic treatment of infectious diseases.

In the form of the invention illustrated,

30 the appliance comprises a tubular body 1 of any suitable length and formed of soft metal or similar material adapting said casing to be bent or deflected as indicated in the figure in order to properly reach the point of application of an antiseptic. 2 designates a pointed tip, preferably of copper and of hollow formation, the same having a threaded connection at 3 with the adjacent end of the casing 1. The tip 2 is formed 35 with an outlet orifice 4 and an inlet orifice 5, said orifice being arranged laterally of the tip and at different distances from the point of the tip, the inlet orifice 5 being located 40 nearest the point of the tip.

45 The tubular casing 1 is bifurcated at its rear end as shown in the drawings, comprising a branch 6 and an extension 7. Both

the branch and extension are terminally enlarged as shown at 8 and internally threaded to receive the threaded ends of nipples 9 and 10 carrying compressible bulbs 11 and 12 of rubber which will expand after they have been compressed and when released. Extending from the nipple 10 through the casing 1 is an inflow tube 13 the discharge end 55 of which is positioned in the outlet orifice 4 while the intake end is secured to nipple 10. An outlet or return flow tube 14 has one end fastened in the nipple 9 and the other end positioned in the inlet orifice 5. 60 Adjacent to the point where the branch 6 joins the casing 1, there is formed a combined finger grip and stop 15 comprising two finger receiving openings 16. This assists the operator in compressing the bulbs 65 11 and 12 and it also forms a cage or limiting stop in order that the degree of penetration may be accurately determined. By a proper manipulation of the bulbs 11 and 12, liquid may be forced through the tube 13 70 out at the orifice 4 and caused to return through the orifice 5 and tube 14 to the bulb 11, and vice versa. This enables liquid to be discharged at various points upon the mucous membrane, thus greatly expediting 75 treatment.

I claim:—

A surgical appliance comprising a bendable tubular member pointed at one extremity and formed adjacent thereto with 80 inlet and outlet orifices, said tubular member being bifurcated at the opposite end thereof, nipples having a threaded and detachable connection with the branches of said casing, compressible bulbs attached to 85 said nipples, and tubes each attached at one end to one of said nipples and extending longitudinally within said tubular member and terminating in juxtaposition to said inlet and outlet orifices, whereby said tubes 90 are independently controllable.

In testimony whereof I affix my signature.

EDWARD H. GALLIGAN.
